UNITED STATES PATENT OFFICE

ERNEST S. MOONEY, OF LOS ANGELES, CALIFORNIA, INCOMPETENT, BY LOS ANGELES FIRST NATIONAL TRUST AND SAVINGS BANK, GUARDIAN, OF LOS ANGELES, CALIFORNIA

TOY ANIMAL

Application filed January 2, 1929. Serial No. 329,855.

This invention relates to toys and more particularly to toy animals of the type having wheels and requiring to be steered, the present improvement being especially associated 5 with the steering mechanism.

The object of the invention is to provide novel and attractive features in the toy from the standpoint of a child, to provide a simple, inexpensive and efficient steering mechanism, and to impart interesting movements to the toy suggestive of the animal represented thereby.

Primarily the invention resides in an animal body having a head, a wheel to be steered, 15 a steering post extending to said head, and laterally disposed steering arms connected with the post and preferably extending into slots representing the mouth. According to one form the arms are connected with opposing resilient elements which serve to balance each other and to tend to maintain the steering wheel in straight-ahead position or to return it to such position.

The improvement also includes movable 25 ears or like members, the connections simulating a bridle and being connected with said ears to move the latter when the device is put through steering movements, and in the preferred form the resilient elements also have 30 connections with said ears in such manner that the ears tend to be returned to normal position when the steering mechanism is returned. The invention resides also in such other novel features of construction and combinations of parts as may be elsewhere herein 35 set forth.

In the accompanying drawings wherein one embodiment of the invention is shown 40 merely by way of illustration;

Fig. 1 is a side elevation of a hobby horse equipped with the present invention.

Fig. 2 is a front elevation thereof.

Fig. 3 is a perspective view of the head.

Fig. 4 is a vertical sectional detail through 45 the head on line 4—4 of Fig. 3.

The body 10 of the toy animal or hobby horse is provided with a head 10', while the rear legs are equipped with wheels 12 and the front legs with a steering wheel 14, the 50 device being adapted to be propelled by the

rider through the medium of any simple drive such as chain 15, gear 16, sprocket 17 and pedal drive 18.

The front or steering wheel 14 is carried by a pair of forks 20 fixed on a steering post 22 journaled in a suitable bearing 24 mounted in a cross plate 25 on the front legs of the horse. The upper end of post 22 projects into and is adapted to rotate in a socket 26 in the head 10' of the horse, the upper end of said socket being closed by a cover plate 28. The uppermost portion of the post 22 is split longitudinally to provide slots 29' in which is fixed a twisted cross bar 30 which projects laterally through and works in slots 32 representing the horse's mouth, the bar 30 thereby indicating a bit. The ends of the projecting arms thus formed by this cross bar, are provided with steering reins 34 connected with holes in the bar ends by means of snap hooks 35, while rings 36 mounted in holes nearer to the head serve to connect straps 38 which simulate parts of a bridle. The rear ends of the straps 38 are secured to the lower ends of pieces 40 which represent the horse's ears, these ears being pivoted at 42 above the points of connection with straps 38. An elastic band 44 which is fixed to the back of the head at 45 as by means of a screw or tack is also connected with the lower ends of the respective ears and with the rear ends of the straps 38, this band serving primarily to tend to return all parts to normal or straight-ahead position.

In operating the toy, the rider, who is positioned on the seat —S— and propels the device through pedals 18, steers the horse through the medium of the reins 34 which act through the medium of the bit-forming bar 30 to rotate the steering post 22 and front wheel 14, the arms of said bar working in the mouth-forming slots 32. As one arm of the bar is pulled rearward by the respective rein 34, the arm and the strap 38 on the other side of the head are thereby pulled forward which causes the ear 40 on said other side to swing rearward about its pivot 42, the respective portion of the elastic band 44 being at the same time stretched and placed under tension, while the other elastic portion re-

mains unaffected by reason of the fixed connection at 45, the strap 38 on the un tensioned side becoming slack and looping or sagging. When the mentioned rein is released the elastic portion 44 which is under tension will tend to return all parts to normal position including the respective ear 40 and the steering mechanism. Thus as the toy is steered to right and left, the ears 40 are moved and the elastic portions 44 are respectively tensioned to return the ears to normal positions, and also to assist steering straight ahead.

What is claimed is:

- 15 1. A toy animal having a front wheel and a head, ears movably mounted on said head, a steering post connected with said wheel to steer the latter, said steering post being journaled in the head, said head being slotted to simulate a mouth, arms connected with said post to actuate the same and projecting from the mouth, connections between said ears and arms to move the ears when the arms are actuated, and reins connected with said arms.
- 20 2. A vehicle of the class described comprising a body member simulating an animal having a head, a steering post having a wheel on its lower end, the upper end of said post being journalled in the animal's head, arms extending at right angles from said post, reins connected to said arms for turning said post to steer the vehicle, and resilient means connected to the arms and the animal's head to assist return of the steering post to normal position.

In testimony whereof it affixes its signature.
